UNITED STATES PATENT OFFICE

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS OF DISTILLING BITUMEN

Application filed December 18, 1925, Serial No. 76,171. Renewed May 15, 1931.

This invention relates to improvements in process of distilling bitumen and products derived thereby, and is more particularly adapted to the distillation of bituminous materials, such as coal, asphaltic materials, tars, or the like, in the presence of air, steam, and heated petroleum. As far as I am aware, I produce certain new products from the use of the process hereinafter set forth.

19 First I produce a large quantity of incondensable gas sufficiently high in heat units as to be adapted for industrial purposes in burning, and thus avoiding any or much enrichment of the gas.

25 Second, I produce a motor fuel having anti-knock properties, in that it contains a considerable percentage of nitrogen and phenolic compounds, and saturated and aromatic hydrocarbons.

30 Third, I produce alcohols, aldehydes and organic acids.

Fourth, I produce a bed of bituminous material, such as coke which has been largely freed of its evaporable hydrocarbonaceous constituents.

The invention will be more readily understood from the accompanying drawing, in which the single figure shows a somewhat diagrammatic view, partly in side elevation 35 and partly in vertical section.

Referring to the drawing, 1 designates a furnace in which is mounted a suitable heating coil 2. Oil is fed to the coil through feed line 3 connected to raw oil pump 4 leading to any suitable source of supply (not shown), as, for example, gas oil or fuel oil.

The oil from the coil passes through transfer line 5, controlled by throttle valve 6 to a combustion chamber 7, which chamber is 40 preferably internally insulated as shown at 8. Any liquid residue may be drawn off of the chamber 7 through drawoff pipe 9 controlled by throttle valve 10.

Vapors pass out of the upper end of the chamber 7 through vapor line 11, controlled by throttle valve 12, and thence to the lower part of a dephlegmator 13. The reflux condensate is drawn out through the lower part of the dephlegmator through pipe 14 controlled by throttle valve 15, which pipe 14 is

preferably provided with a reflux pump 16, whereby the reflux condensate is returned to the heating coil 2 via the feed line 3. If desired, the reflux condensate may be drawn out of the system through branch pipe 17 by 55 suitably manipulating the valves 18, 15 and 19, as will be clearly seen from the drawing.

Steam saturated or superheated is introduced into the lower part of the chamber 7 through steam line 20 controlled by throttle valve 21 and leading to any source of steam supply (not shown). Similarly air may be forced into the chamber 7 by means of air pipe 22, having throttle valve 23 and connected to air pump 24.

The vapors which are not liquefied in the dephlegmator pass out of the upper end thereof through pipe 25 controlled by throttle valve 26, which pipe 25 leads to condenser coil 27, which in turn connects to receiver 28. This receiver 28 is provided with liquid draw-off pipe 29 controlled by throttle valve 30 and gas outlet pipe 31 controlled by valve 32. The gas holder 33 is also provided and connected to the gas outlet 75 pipe 31.

The process may be carried out as follows: Bituminous material, such as, for example, coal is charged into the insulated chamber 7, fuel oil is fed through the line 3 to the 80 heating coil 2, where the oil is heated to a transfer temperature of, say, 800 deg. F. The oil passes into the bed of coal and tends to dissolve out some of the hydrocarbonaceous material, and also to distill off some of 85 the same.

At the same time regulated quantities of air are introduced into the bed of coal, which air acts chemically to promote combustion and burn some of the coal and some of the 90 petroleum.

At the same time steam is introduced into the chamber 7, and the action of the highly heated contents of the chamber 7 breaks down the steam into hydrogen and carbon 95 monoxide. The temperature of the contents of the chamber 7 may run as high as say 1800 deg. F., or more.

The petroleum oil vapors, the vapors from the hydrocarbonaceous constituents of the 100

coal, together with the gases formed from breaking down the steam, as well as other fixed gases formed by the operation, all pass into the dephlegmator. Here the heavy constituents which are not sufficiently cracked are condensed, the amount of condensation depending upon the temperature at which it is dephlegmated. The reflux condensate is drawn out of the lower part of the dephlegmator and may be re-run through the coil 2, or carried off to storage or elsewhere. The uncondensed vapors pass through the condenser into the receiver, while the incondensable gas goes to the gas holder shown 15 in the drawing.

By means of the present process I produce the various products stated in the earlier part of the specification, and it is not necessary to again repeat them.

20 The whole system is preferably maintained under a substantial superatmospheric pressure, say, for example, 100 pounds to the square inch.

I claim as my invention:

25 1. A process for simultaneously heating a hydrocarbon liquid and a quantity of bituminous material, which comprises the maintaining of a mass of bituminous material in a closed chamber, the heating of the hydrocarbon liquid to a cracking temperature in a separate zone, subsequently bringing the heated hydrocarbon liquid into physical contact with the bituminous material by introducing it into the lower portion of said closed 30 chamber, removing vaporous constituents generated from the oil and bituminous materials from said closed chamber and, during the operation of the process, subjecting the bituminous material and heated hydrocarbon 35 liquid and in said closed chamber to the action of steam and controlled combustion by introducing thereto controlled quantities of steam and air, regulating the combustion in said closed chamber so that the temperature 40 of the material therein is maintained in excess of 1000° F. and maintaining the material in said closed chamber under a superatmospheric pressure.

45 2. A process for simultaneously treating a hydrocarbon liquid and a quantity of bituminous material, which comprises the maintaining of a mass of bituminous material in a closed chamber, the heating of the hydrocarbon liquid to a cracking temperature in a separate zone, subsequently bringing the heated hydrocarbon liquid into physical contact with the bituminous material by introducing the heated hydrocarbon liquid into the lower portion of said closed chamber before any substantial evolution of vapors from the liquid, removing vaporous constituents generated from the liquid and bituminous material from said closed chamber and, during the operation of the process, subjecting the bituminous material and heated hydro-

carbon liquid in said closed chamber to the action of steam and controlled combustion, by introducing thereto controlled quantities of steam and air, regulating the combustion in said closed chamber so that the temperature of the material therein is maintained in excess of 1000° F., and maintaining the material in said closed chamber under a superatmospheric pressure.
